UNITED STATES PATENT OFFICE.

WILLIAM HEATON, OF NEAR ALLERTON, ILLINOIS.

DESIGN FOR A CATTLE-SHED.

SPECIFICATION forming part of Design No. 31,252, dated July 18, 1899.

Application filed June 8, 1899. Serial No. 719,848. Term of patent 14 years.

To all whom it may concern:

Be it known that I, WILLIAM HEATON, a citizen of the United States, residing near Allerton, in the county of Vermilion and State 5 of Illinois, have invented and produced a new and original Design for a Cattle-Shed, of which the following is a specification, reference being had to the accompanying drawings, forming part thereof, in which—

Figure 1 is a side view, and Fig. 2 a top plan view, of a shed, showing my new design.

The leading feature of the design consists in the shed, presenting in end view the horizontal beam 1 below the inclined roof-beams 5 2 and 3, the inclined crossed beams 4 and 5, and the inclined beams 6, extending between the horizontal and roof beams, together with the base having the extension B', with the curved edge B².

The shed has its ends A converging from its outer side B to its inner side C, the base at the side B being extended laterally at B'

and curved on its outer edge B². The inner side C is formed on a straight line. The wall B³ at the outer side of the shed inclines outward toward its upper end, and the roof has the short inclined side D and the long inclined side E, the latter extending from the ridge F, which is comparatively near the side B, to what I have termed the "inner" side of the 30 shed.

In plan view, as shown in Fig. 2, the shed presents an appearance simulating a trapezoid.

Having described my invention, what I 35 claim as new, and desire to secure by Letters Patent, is—

The design for a cattle-shed, as herein shown and described.

WILLIAM HEATON.
